United States Patent Office.

NATHAN H. EDGERTON, OF POTTSVILLE, PENNSYLVANIA.

Letters Patent No. 65,799, dated June 18, 1867.

IMPROVED CAR-REPLACER.

The Schedule referred to in these Letters Patent and making part of the same.

TO ALL WHOM IT MAY CONCERN:

Be it known that I, NATHAN H. EDGERTON, of Pottsville, Schuylkill county, in the State of Pennsylvania, have invented a new and improved Mode of Replacing Railroad Cars upon the Track; and I do hereby declare the following is a full and exact description thereof, reference being had to the accompanying drawings, and to the letters of reference marked thereon.

The nature of my invention consists in constructing blocks, plated and inclined, and having secured to one of each pair a canting-block, by which arrangement a car may be replaced upon the track. Many devices are designed for this purpose, but the weight of them has always been a serious drawback against their general use. Some of them are made with heavy flanges cast or bolted on the inclined planes, and secured to the rail by a hook or keys. This plan requires two pairs of right and left-hand blocks in order to put the car on from either direction, and being so heavy, it is necessary to leave them at the depots, to be brought by a special wrecking train. By my invention this is obviated, and they can easily be carried on the tender, and handled by the ordinary crew accompanying the train; thus saving the time which would otherwise be spent in sending for the wrecking crew. My invention combines this requisite of lightness and utility.

To enable others skilled in the art to make and use my invention, I will proceed to describe its construction and operation.

Figure 1 is a plan.

Figure 2 is an elevation of the inside block.

Figure 3 is an elevation of the outside block.

Figure 4 is an end view of the outside block.

Figure 5 is a cross-section on an enlarged scale.

A A' are the rails; B, the car off the track; C is one of the inclined blocks, D the other. The block C is of hard wood, plated with iron. The incline from e to e^1 is long, the other from e^1 to e^2 is short and steep. This block is made so that the apex e^1 is about one inch lower than the rail A. This block is placed, as shown, about two inches from the rail A, and kept at that distance by the projecting pins h h . It may also be spiked on the inside, if necessary. The other block D is placed close alongside the corresponding rail A', is similarly plated, and inclined from e to e^1 , except the apex e^1 in this case stands some two inches above the rail. The elongated foot m carries a canting-block, K, which I will describe particularly, as it is an essential feature. The flat base of block K has a projecting pin, n , either round or square, fitting into a corresponding mortise in foot m . It stands up some five or six inches above the rail, with an inclined face towards the rail. The centre is mortised at S to receive the eye of a hook, O, and a pin or bolt driven through the said eye secures it to the block K. This canting-block K is placed at such a distance from the apex e^1 , that the side of the wheel P will just strike the said block as the wheel begins to descend from the apex e^1 ; and the falling of the wheel materially assists the lateral or sideway motion derived from the block K. As this said canting-block is detachable from its bed, the inclined block D can be turned end for end, and still the block K will face and clasp the rail in the same manner, thus accomplishing the object of replacing the car from either direction, thus dispensing with a pair of right and left-hand blocks.

To use my invention, place the incline C between the rails, about two inches from the rail A. Place the incline D outside and close alongside the rail A', and a little in advance of the incline C. Take the block K and catch the hook O over the rail, and drop the pin n into its corresponding mortise in foot m . A spike may be driven against the side of block D to secure it more firmly against the rail. Now draw the car up the inclines and it will be replaced upon the track.

What I claim as my invention, and desire to secure by Letters Patent, is—

1. I claim the reversible and detachable canting-block K, secured to the rail A' and the depressed foot m ; substantially as described.
2. I claim the plated incline D, having a depressed projecting foot, m , in combination with a canting-block, K, adjusted substantially as described.
3. I claim the combination and arrangement of my second claim with the inclined block C, when both are constructed and operating substantially as described.
